DESIGN FOR A SHOE

Dave Gilbert, New York, N. Y.

Application October 19, 1938, Serial No. 80,539

Term of patent 3½ years

To all whom it may concern:

Be it known that I, Dave Gilbert, a citizen of the United States of America, residing in city of New York, county of New York, and State of New York, have invented a new, original, and ornamental Design for a Shoe of which the following is a specification, reference being had to the accompanying drawing, forming part thereof.

Fig. 1 is a plan view of a shoe showing my new design.

Fig. 2 is a side elevation thereof.

Fig. 3 is a bottom view in perspective.

I claim:

The ornamental design for a shoe, substantially as shown.

DAVE GILBERT.
